MATERNITY GIRDLE

Beatrice Wohlman, New York, N. Y.

Application December 1, 1949, Serial No. 130,479

8 Claims. (Cl. 2—41)

1

This invention relates to maternity girdles.

An object of this invention is to provide a maternity girdle which shall have a front panel which stretches up and down but not sideways, said panel being in the form of an insert in the front portion of the girdle and extending from the upper edge of the girdle to a point short of the bottom edge of the girdle, said front portion of the girdle being made of cloth which stretches more easily sideways than up and down.

Another object of this invention is to provide a maternity girdle of the character described having side panels likewise made of cloth which stretches more easily sideways than up and down, and said side panels being interconnected by a back panel which stretches up and down but not sideways.

Another object of this invention is to provide a maternity girdle of the character described in which the side panels are provided with lacing means invisible to the outside when the lacing is drawn tight, and the lacing being more to the rear of the girdle than to the front so as not to press against the abdominal portion of the body, and which will contact the hips of the body which will be less affected by the pressure.

Yet another object of this invention is to provide a girdle of the character described having inner lining flaps to underlie the lacing and serve as a protection for the body.

Still another object of this invention is to provide in the back portion of the girdle a plurality of bones or stiffeners which are located at the small of the back, the arrangement being such that the bones will not retard up and down give or stretch of said back panel. The pockets for the bones comprise elastic strips stitched at its side edges and ends to said back panel, and said pocket being stretchable up and down with the back panel.

Yet another object of this invention is to provide a garment of the character described having lacing at both sides so that as the lacing is opened up to expand the garment the front of the girdle will keep centered as well as the back of the girdle.

Still another object of this invention is to provide a garment of the character described having elastic strips stitched to both the top and bottom edges of the garment at the inside thereof so as to give with the front and side panels or portions of the garment.

A still further object of this invention is to provide a girdle of the character described in which zig zag stitching is used throughout, and

2

in which the front insert is attached to the front panel by faggoting, and in which the side panels are attached to the front panel by faggoting.

Yet another object of this invention is to provide a garment of the character described having a pair of symmetrical reinforcing gussets stitched to the innerside of the front portion of the garment and extending from the sides of the insert to the side panels and said gussets being made of cloth stretchable sideways and being somewhat curved upwardly and outwardly so as to support the body of the wearer in the region of the pelvis. The gussets are less stretchable sideways than the cloth of the two front panels which comprise the front portion of the girdle, so as to better support the pelvic region or abdomen of the wearer.

Yet another object of this invention is to provide a garment of the character described in which the upper edge of the front of the garment and the upper edge of the back of the garment are curved upwardly or extended upwardly so as to extend the effect of the girdle upwardly on the body.

Still another object of this invention is to provide a girdle of the character described in which the front portion of the garment comprises a pair of front panels stitched together below the lower end of the insert and in which the stitched together edges normally before stitching form an inverted V with the apex at the lower end of the insert, and the lower ends of said edges being brought together and said edges stitched together so as to constrict the lower end of the girdle.

A yet further object of this invention is to provide a durable girdle of the character described which shall be attractive in appearance, which shall be long wearing, comfortable in use and yet practical and efficient to a high degree.

Other objects of this invention will in part be obvious and in part hereinafter pointed out. The invention accordingly consists in the features of construction, combinations of elements, and arrangement of parts, which will be exemplified in the construction hereinafter described, and of which the scope of invention will be indicated in the following claims:

In the accompanying drawings in which is shown various illustrative embodiments of this invention,

Fig. 1 is a front elevational view of a maternity girdle embodying the invention,

Fig. 2 is a rear elevational view thereof,

Fig. 3 is a front view of the girdle turned in-

side out and showing the flaps which underlie the lacing stretched out,

Fig. 4 is a partial side view of the girdle,

Fig. 5 is a partial inside view of one side of the girdle,

Fig. 6 is an enlarged cross-sectional view taken on line 6—6 of Fig. 1,

Fig. 7 is an enlarged partial cross-sectional view of part of the girdle, and

Fig. 8 is an enlarged partial perspective cross-sectional view of another part of the girdle.

Referring now in detail to the drawing, 10 designates a girdle embodying the invention. The same comprises a front portion 11 comprising a pair of symmetrical front panels 12. Between 15 the panels 12 is an insert 13. The insert 13 extends from the upper edge of the girdle to a point 14 spaced above the lower edge of the girdle. The insert 13 is made of satin lastex or the like cloth which stretches up and down but not sideways. The insert 13 is wider at its upper edge, has a constricted middle portion and its lower end is somewhat leaf shaped. It is connected to the adjacent edges of the front panels 12 by faggotting 15. The outer edges of the insert 13 are all folded inwardly against the rear surface of said insert and attached thereto by lines of zig zag stitching 16.

The front panels 12 are made of a cloth that stretches more easily from side to side than up and down. The panels 12 are stitched together by a central line of faggotting 17 extending from the point 14 to the lower edge of the girdle. The panels 12 are cut in such a way that the edges thereof connected by faggotting 17 form an inverted V with the apex at the point 14, before said edges are stitched together. Said edges are then brought together and connected by faggotting 17 thereby constricting or pulling in the lower edge of the girdle.

Connected to the outer ends of the front panels 12 by lines of faggotting 19, are similar symmetrically disposed side panels 20 likewise made of cloth which stretches more easily from side to side than up and down. In other words the cloth 20 may be the same as the cloth 12 and stretches the same way. The outer edges of the panels 12 may be turned inwardly against the rear surface of said panels and stitched thereto by lines of zig zag stitching 21. The adjacent edges of panels 20 may likewise be folded inwardly against the rear surfaces of said side panels and stitched thereto by lines of zig zag stitching 22. Each panel 20 may be made of two pieces of cloth which extend from the lower to the upper edge of the garment. The forward piece is designated by the numeral 24 and the rearward piece by numeral 25. The pieces 24, 25 are stitched together as at 26 at their lower ends. The adjacent edges are turned back against the rear surface of pieces 24 and 25 and stitched to said pieces by lines of stitching 27 and 28 respectively. Above the line of stitching 26 the pieces 24 and 25 are split, forming edges 29 and 30 respectively extending to the upper end of the girdle. Stitched to the inner surfaces of said edges 29 and 30 are strips of tape 34 and 35, respectively, to which are attached eyelets 36. The eyelets are connected by lacing 37.

Stitched to each piece of tape 34 is an inner flap 40 which lies against the inner side of the lacing. It will be noted that the lacing 37 is located rearwardly of the sides of the girdle so as to contact the hips and legs of the wearer

and not the abdomen. The flaps 40 extend rearwardly toward each other and as the girdle is adjusted to increase its girth, the flaps will still protect the wearer from contact with the lacing or eyelets. The lower ends of the tapes 34 and 35 are stitched to piece 20 by stitching 41. The rear edges of the pieces 25 are stitched to a rear panel 42 which interconnects the side panels and may be made of satin lastex stretchable up and down but not sideways.

Stitched to the lower edge of the garment all around is an elastic strip 43. At the upper edge of the garment an elastic strip 44 is stitched to the panels 13 and 12 and pieces 24. A second elastic strip 45 is stitched at the upper end of the garment to the pieces 25 and rear panel 42. The pieces 25 are stitched to the rear panel 42 along the seams 48. The adjacent edges of pieces 25 and panel 42 are folded rearwardly against the inner surfaces thereof and stitched in place by lines of stitching 49 and 50, respectively.

Overlying the upper portion of the seam 48 and stitched to the adjacent edges of pieces 25 and panel 40 are strips of tape 52 forming longitudinal pockets in which be placed stiffeners 53. The pockets 52 extend from the upper end of the garment about $\frac{1}{3}$ of the way down towards the bottom.

Stitched to the inner surface of the rear panel 42 are a pair of elongated elastic strips 55. The side edges of elastic strips 55 are stitched to the panel 42 along parallel lines of zig zag stitching 56, forming pockets to receive bones or stiffeners 57. The elastic strips 55 are stretchable up and down with the panel 42 and the bones 57 do not hamper the stretching of the pockets. The pockets or strips 55 are symmetrically disposed with respect to the back of the girdle and are located adjacent the small of the back.

Means is provided to support the pelvic region of the body. To this end there is stitched to the inner surface of the panels 12 a pair of similar symmetrically disposed gussets 60. The upper and lower edges of gussets 60 are stitched to the panels 12 by lines of stitching 61 and 62, respectively. Said gussets 60 are also stitched to the panels 12 at their ends. It will be noted that the edge of the panels 12 all around the insert 13 are folded back at the inside and stitched in place by lines of zig zag stitching 70. The lines of stitching 70 stitch the inner ends of the gussets 60 in place. At their outer side the gussets are stitched in place by said lines of stitching 21. The gussets are made of satin lastex or like cloth, stretchable sideways but not up and down. However, the stretch of the gussets sideways is less than the stretch of the panels 12 sideways. It will be noted that the gussets 60 are inclined generally upwardly and rearwardly so as to help support the pelvic region of the wearer. The gussets 60 are located above the lower edges of the panels 12 and somewhat above the lower end of the insert 13. Both the upper and lower ends of the panels 12, 20 and 42 are folded back inwardly and stitched in place by lines of zig zag stitching 72.

It will be noted that the upper end of the insert 13 is curved upwardly as designated by numeral 76. Also the upper end of the center of the panel 42 is somewhat upwardly curved as at 77.

It will now be understood that the front in-

sert panel stretches up and down and not sideways and is an insert in the front panels which stretch more sideways than up and down. The side lacings and flap allow opening up of garment. The lacing is invisible from the outside and is located toward the back of the garment than the front. The bones at the small of the back do not retard up and down give. The lacing is at both sides of the garment and keep the garment centered. The side panels 20 stretch more sideways than up and down. Attached to the lower end of the garment are the usual hose supports 80.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

While the insert 13 has been described as being made of material which stretches up and down and not sideward, said insert may also be made of a material which stretches more easily up and down than sideways, in other words, said material may have just a little stretch sideways and may be much more easily stretchable up and down. Furthermore, the rear panel 42 instead of being stretchable only up and down and not sideways may be made of cloth which is stretchable more easily up and down than sideways, in other words, it may be made of a cloth which stretches easily up and down but must be pulled hard in order to stretch sideways.

It will also be noted that while the gussets 60 are described as being stretchable sideways but not up and down, they may also be made of cloth which is stretchable more easily sideways than up and down.

Having thus described my invention I claim as new and desire to secure by Letters Patent:

1. A girdle comprising a front section consisting of one piece side panels stretchable transversely, and an intermediate one piece panel having its upper end even with upper ends of the side panels and its lower end spaced upwardly from lower ends of the side panels, said intermediate panel being stretchable up and down and being gradually reduced in width from its upper end for a portion of its length and then gradually increasing in width downwardly and forming a widened lower portion having a tapered lower end, said side panels having reversely curved inner side edges sewed to side edges of the intermediate panel and extending towards each other about the lower end of the intermediate panel and terminating in vertical edges sewed together between the lower end of the front section, side sections stretchable transversely and having front side edges sewed to outer side edges of the side panels of said front section, and a rear section stretchable up and down and having side edges sewed to rear side edges of the side sections.

2. The structure of claim 1 wherein the side panels of the front section carry elastic reinforcing bands sewed along their margins to inner surfaces of the said side panels and extending transversely thereof from sides of the said

widened lower portion of the intermediate panel in upwardly spaced relation to the lower end of the intermediate panel and disposed at an upward incline towards their outer ends.

3. The structure of claim 1 wherein the side sections consist of front and rear panels extending vertically in side by side relation to each other, the front panels of said side sections being of greater width than the rear panels 10 of said side sections and extending around the side of the girdle to the rear thereof, lower end portions of inner side edges of the front and rear panels being sewed together for a short distance and for the remainder of their length, the said front and rear panels being free and spaced from each other and provided with eyes projecting from their inner side edges in vertically spaced relation to each other, and lacing means secured to outer edges of the front and rear panels for variable adjustment of the girdle.

4. A girdle comprising a front section consisting of a pair of one piece side panels, and an intermediate one piece panel having its upper end even with the upper ends of the side panels, and its lower end spaced upwardly from the lower ends of the side panels, said intermediate panel being stretchable more easily up and down than sideways, said side panels having 25 inner side edges sewed to the side edges of the intermediate panel and extending toward each other about the lower end of the intermediate panel and terminating in vertical edges sewed together between the lower end of the intermediate panel and the lower ends of the side panels, said side panels being stretchable more easily transversely than up and down, side sections stretchable more easily transversely than up and down and having front side edges sewed 30 to outer side edges of the side panels of said front section, and a rear section stretchable more easily up and down than transversely and having side edges sewed to the rear side edges of said side sections, the side panels of the front section carrying elastic reinforcing bands sewed along their margins to inner surfaces of said side panels and extending transversely thereof from sides of the intermediate panel in upwardly spaced relation to the lower end of said intermediate panel and disposed at an upward incline toward their outer ends.

5. A girdle comprising a front section consisting of a pair of one piece side panels, and an intermediate one piece panel having its upper end even with the upper ends of the side panels, and its lower end spaced upwardly from the lower ends of the side panels, said intermediate panel being stretchable more easily up and down than sideways, said side panels having 55 inner side edges sewed to the side edges of the intermediate panel and extending toward each other about the lower end of the intermediate panel and terminating in vertical edges sewed together between the lower end of the intermediate panel and the lower ends of the side panels, said side panels being stretchable more easily transversely than up and down, side sections stretchable more easily transversely than up and down and having front side edges sewed 60 to outer side edges of the side panels of said front section, and a rear section stretchable more easily up and down than transversely and having side edges sewed to the rear side edges of said side sections, the side panels of the front section carrying elastic reinforcing bands sewed 65 to outer side edges of the side panels of said front section, and a rear section stretchable more easily up and down than transversely and having side edges sewed to the rear side edges of said side sections, the side panels of the front section carrying elastic reinforcing bands sewed 70 to outer side edges of the side panels of said front section, and a rear section stretchable more easily up and down than transversely and having side edges sewed to the rear side edges of said side sections, the side panels of the front section carrying elastic reinforcing bands sewed 75 to outer side edges of the side panels of said front section, and a rear section stretchable more easily up and down than transversely and having side edges sewed to the rear side edges of said side sections, the side panels of the front section carrying elastic reinforcing bands sewed

along their margins to inner surfaces of said side panels and extending transversely thereof from sides of the intermediate panel in upwardly spaced relation to the lower end of said intermediate panel and disposed at an upward incline toward their outer ends, the reinforcing bands being stretchable transversely less easily than the side panels of the front section.

6. A girdle comprising a front section consisting of a pair of one piece side panels, and an intermediate one piece panel having its upper end even with the upper ends of the side panels, and its lower end spaced upwardly from the lower ends of the side panels, said intermediate panel being stretchable more easily up and down than sideways, said side panels having inner side edges sewed to the side edges of the intermediate panel and extending toward each other about the lower end of the intermediate panel and terminating in vertical edges sewed together between the lower end of the intermediate panel and the lower ends of the side panels, said side panels being stretchable more easily transversely than up and down; side sections stretchable more easily transversely than up and down and having front side edges sewed to outer side edges of the side panels of said front section, and a rear section stretchable more easily up and down than transversely and having side edges sewed to the rear side edges of said side sections, the side sections consisting of front and rear panels extending vertically in side by side relation to each other, the front panels of the side sections being of greater width than the rear panels of said side sections and extending to the back of the girdle, lower end portions of the inner side edges of the front and rear panels of said side sections being sewed together for a short distance and for the remainder of their length, said front and rear panels of said side sections being free and spaced from each other and provided with eyes at their inner side edges in vertically spaced relation to each other, and lacing means secured to outer edges of the front and rear panels for variable adjustment of the girdle.

7. A girdle comprising a front section consisting of a pair of one piece side panels, and an intermediate one piece panel having its upper end even with the upper ends of the side panels, and its lower end spaced upwardly from the lower ends of the side panels, said intermediate panel being stretchable more easily up and down than sideways, said side panels having inner side edges sewed to the side edges of the intermediate panel and extending toward each other about the lower end of the intermediate panel and terminating in vertical edges sewed together between the lower end of the intermediate panel and the lower ends of the side panels, said side panels being stretchable more easily transversely than up and down, side sections stretchable more easily transversely than up and down and having front side edges sewed to outer side edges of the side panels of said front section, and a rear section stretchable more easily up and down than transversely and having side edges sewed to the rear side edges of said side sections, the side sections consisting of front and rear panels extending vertically in side by side relation to each other, the front panels of the side sections being of greater width than the rear panels of said side sections and extending to the back of the girdle, lower end portions of the inner side edges of the front and rear panels of said side sections being

sewed together for a short distance and for the remainder of their length, said front and rear panels of said side sections being free and spaced from each other and provided with eyes at their inner side edges in vertically spaced relation to each other, and lacing means secured to outer edges of the front and rear panels for variable adjustment of the girdle, flaps being attached to the front panels of the side sections, and said flaps extending rearwardly and underlying the lacing.

8. A girdle comprising a front section consisting of a pair of one piece side panels, and an intermediate one piece panel having its upper end even with the upper ends of the side panels, and its lower end spaced upwardly from the lower ends of the side panels, said intermediate panel being stretchable more easily up and down than sideways, said side panels having inner side edges sewed to the side edges of the intermediate panel and extending toward each other about the lower end of the intermediate panel and terminating in vertical edges sewed together between the lower end of the intermediate panel and the lower ends of the side panels, said side panels being stretchable more easily transversely than up and down, side sections stretchable more easily transversely than up and down and having front side edges sewed to outer side edges of the side panels of said front section, and a rear section stretchable more easily up and down than transversely and having side edges sewed to the rear side edges of said side sections, the side panels of the front section carrying elastic reinforcing bands sewed along their margins to inner surfaces of said side panels and extending transversely thereof from sides of the intermediate panel in upwardly spaced relation to the lower end of said intermediate panel and disposed at an upward incline toward their outer ends, the side sections consisting of front and rear panels extending vertically in side by side relation to each other, the front panels of the side sections being of greater width than the rear panels of said side sections and extending back to the girdle, lower end portions of the inner side edges of the front and rear panels of said side sections being sewed together for a short distance and for the remainder of their length, the front, side and rear panels of said side sections being free and spaced from each other and provided with eyes at their inner side edges in vertically spaced relation to each other, and lacing means secured to outer edges of the front and rear panels of said side sections for variable adjustment of the girdle.

BEATRICE WOHLMAN.
